UNITED STATES PATENT OFFICE.

WILLIAM T. SMITH AND WILLIAM G. OLDHAM, OF PHILADELPHIA, PENNSYLVANIA, ASSIGNORS TO WILLIAM T. SMITH & SON, OF SAME PLACE.

DESIGN FOR A WOVEN FABRIC.

SPECIFICATION forming part of Design No. 22,160, dated January 24, 1893.

Application filed December 30, 1892. Serial No. 456,848. Term of patent 3½ years.

To all whom it may concern:

Be it known that we, WILLIAM T. SMITH and WILLIAM G. OLDHAM, citizens of the United States, residing at Philadelphia, in the county of Philadelphia and State of Pennsylvania, have invented and produced a new and original Design for a Woven Fabric, of which the following is a specification, reference being had to the accompanying drawing.

o The leading feature of our design is a center representation of water fowls, and plants, with scenery in the back-ground, surrounded by a floral border, the whole as illustrated by

the accompanying drawing, which is sufficient to enable others skilled as fancy weavers to produce our invention.

What we claim as new, and desire to secure by Letters Patent, is—

The design for a woven fabric, as shown in the accompanying drawing.

W. T. SMITH.
W. G. OLDHAM.
